UNITED STATES PATENT OFFICE

160,719

GAME BOARD

Emma E. Kloss, Chicago, Ill.

Application February 17, 1950, Serial No. 7,994

Term of patent 14 years

(Cl. D34—5)

To all whom it may concern:

Be it known that I, Emma E. Kloss, a citizen of the United States, residing at Chicago, Cook County, State of Illinois, have invented a new, original, and ornamental Design for Game Board, of which the following is a specification, reference being had to the accompanying drawing, forming a part hereof, wherein,

Fig. 1 is a top plan view of a game board showing my new design; and

Fig. 2 is an edge view thereof.

I claim:

The ornamental design for a game board, as shown.

EMMA E. KLOSS,
